UNITED STATES PATENT OFFICE.

GEORGE A. SULTER, OF CLEVELAND, OHIO.

DESIGN FOR A BICYCLE-HANDLE.

SPECIFICATION forming part of Design No. 26,891, dated April 13, 1897.

Application filed September 21, 1896. Serial No. 606,588. Term of patent 7 years.

To all whom it may concern:

Be it known that I, GEORGE A. SULTER, a citizen of the United States, residing in Cleveland, in the county of Cuyahoga and State 5 of Ohio, have invented a new and useful Design for Bicycle-Handles, of which the following is a specification, reference being had to the accompanying drawings, showing said design.

Figure 1 is an edge elevation of my new design for bicycle-handles; and Fig. 2 is a plan view thereof, these two views being deemed necessary to clearly and fully illustrate my design.

The leading feature of my design, as shown in these illustrations, consists in the contour or shape of the handle, the outlines of which, when viewed in edge elevation, fall within parallel lines horizontally and curved, and assume an outline in both views, substantially as shown.

A represents the front inwardly curved or concave portion of the handle constituting

my design, and B is the rear convex portion thereof. These portions together constitute 25 a single handle, convex on one side and concave on the other and both sides fashioned in tubular or cylindrical form, resembling a round rod in appearance and uniform in cross-section, both sides lying in the same 30 plane when viewed from the edge thereof. An inclined stem C is also shown, which conforms to the outline of the other portions of the handle, but is straight rather than curved and in elevation of the handle is shown be- 35 neath the horizontal portions A and B.

What I claim is—

The design for a handle for bicycles, substantially as shown and described.

Witness my hand to the foregoing specification this 16th day of September, 1896.

GEORGE A. SULTER.
